UNITED STATES PATENT OFFICE.

ELISHA SUMPTION, OF SOUTH BEND, INDIANA.

IMPROVEMENT IN IRONING APPARATUS.

Specification forming part of Letters Patent No. 135,606, dated February 4, 1873.

To all whom it may concern:

Be it known that I, ELISHA SUMPTION, of South Bend, in the county of St. Joseph and State of Indiana, have invented a new and useful Ironing Apparatus for Smoothing Clothes, of which the following is a specification:

Description of the Accompanying Drawing.

Figure 1 is a side elevation as it appears when in operation. Fig. 2 is the table-frame, showing the friction-wheels with the cover or ironing-board detached. Fig. 3 is a side elevation of the wheel B with the cords and side pulleys attached. Figs. 4 and 5 are the supports, in the top of which are slots to guide the movements of the pitman attached to the smoothing-iron, and which also govern the action of the pedals.

General Description.

A is an ordinary table, with a top movable upon four small friction-wheels, *a a*, to the right and left by the hands of the operator, as desired. B is a wooden wheel, fifteen inches in diameter, and one and a fourth inch on the face, on each side of which is attached a small pulley, *b*, all working on a common axle. In the face of said wheel are cut two grooves to receive the cords *c* and *d*. These cords are attached at one end in the grooves in the face of the wheel B at the points marked 1 and 2, while the other ends are attached to the horizontal pitman *e* at the points marked 3 and 4. These cords pass around the wheel B in opposite directions, and pass each other at the top. The cords *f f* are attached, one end in a groove in the pulley *b* on each side of the

wheel B, and the other ends to the peddals *g g* which are fastened in the standard *i*, shown in Fig. 5, and pass through straddle of the standard *j*, shown in Fig. 4, under the table, to the position of the operator; and said standards are held in position by the two side pieces *h h*, in which the axle of the wheel B works, and which connect said standards with the table A by means of iron or other metallic hooks. C is the smoothing-iron, tapering to a point at both ends, so that it will pass over the clothes to be smoothed as well in one direction as another. The horizontal pitman E rests upon the face of the wheel B, and is, at one end, attached to the smoothing-iron C, and is worked back and forth by the action of the operator on the peddals *g g*, and thus giving the necessary motion to the smoothing-iron, while both hands of the operator are free to move the table-cover or ironing-board and adjust the clothing thereon as desired; and when not in use the iron is by the same process drawn back and made to rest upon a small pedestal on a plane with or a little higher than the table.

Claim.

I claim as my invention—

The combination of the table A, the top movable on friction-rollers, with side pieces *h* and standards *i j*, the treadles *g*, cords *f*, wheel B, the pitman E, and the smoothing-iron C, as and for the purpose specified.

ELISHA SUMPTION.
